UNITED STATES PATENT OFFICE

118,467

DESIGN FOR A PEELING MACHINE

Mortimer R. Anstice, Rochester, N. Y., assignor to
Josiah Anstice & Company, Inc., Rochester,
N. Y., a corporation of New York

Application July 25, 1939, Serial No. 86,239

Term of patent 14 years

To all whom it may concern:

Be it known that I Mortimer R. Anstice, a citizen of the United States, residing at Rochester, New York, have invented a new, original, and ornamental Design for a Peeling Machine, of which the following is a specification, reference being had therein to the accompanying drawing, forming part thereof.

In the accompanying drawing:

Fig. 1 is a perspective front view,

Fig. 2 is a top plan view

Fig. 3 is a rear and side perspective view of a peeling machine showing my new design.

I claim:

The ornamental design for a peeling machine, as shown.

MORTIMER R. ANSTICE.
